UNITED STATES PATENT OFFICE.

ELLSWORTH E. FLORA AND JOHN F. MURPHY, OF CHICAGO, ILLINOIS, ASSIGNORS TO THE SEAL & FASTENER CO., OF CHICAGO, ILLINOIS, A CORPORATION OF DELAWARE.

TOOL FOR JOINING METAL-STRAP ENDS.

1,105,191.

Specification of Letters Patent. Patented July 28, 1914.

Application filed September 2, 1913. Serial No. 787,710.

To all whom it may concern:

Be it known that we, ELLSWORTH E. FLORA and JOHN F. MURPHY, citizens of the United States, residing at Chicago, in the county of 5 Cook and State of Illinois, have invented a new and useful Improvement in Tools for Joining Metal-Strap Ends, of which the following is a specification.

This invention relates to an improved construction of tool for joining mutually-overlapping metal straps or strips by crimping them edgewise into infolding contact, thereby locking the parts against relative movement.

15 The method of forming the joint thus referred to is the subject of Letters Patent of the United States No. 1,038,108, granted September 10, 1912; and the present tool is an improvement on the tool set forth in 20 Letters Patent of the United States No. 1,038,109, also granted on that date.

In the accompanying drawings, Figure 1 shows the improved tool, with the jaws closed, by a broken view in front elevation; 25 Fig. 2 is a broken face view, showing the head portion of the tool partly in section, and the jaws open; Fig. 3 is a section on line 3—3, Fig. 1; Fig. 4 is a broken and partly sectional enlarged view of the head-portion 30 of the tool with the jaws open and the work in place between them, to be crimped; Fig. 5 is a similar view showing the jaws closed upon the work to complete the joint; Fig. 6 is a plan view, partly sectional, showing 35 the head with the jaws in the condition represented in Fig. 5, and Figs. 7 and 8 are, respectively, a back view and an edge view showing strap-ends joined together by the interlocking crimps produced by the tool.

40 The handles 9, 9, which may be of any desired length and hollow, as shown, terminate at their forward ends in corresponding segmental gears 10. These handles are pivotally supported through the gear-centers, to 45 house the gears in intermeshing relation between two similar metal side-plates 11, each formed with a forwardly-extending tongue 12, the plates being securely fastened together by a bolt 13 passing at their pointed 50 rear ends through an interposed spacing-sleeve, as shown in Fig. 3. Between the tongues 12 are pivoted, on a bolt 14 passing through them near their forward ends, similar jaws 15, 15, formed with inwardly projecting wedge-shaped lips 16 having curved

edges (shown by dotted representation at 16 in Fig. 6) to adapt them to meet at their central portions when the jaws are closed. The lip-carrying sections of the jaws are preferably formed separately and driven 60 into place, thereby to render them removable when worn out and replaceable by others. From the center of the face of each jaw, beneath the lip, projects a crimping-pin 17 presenting, as its forward end, a 65 short, rounded strap-edge engaging shoulder at the base of the beveled edge of the lip. Arms 18 on the jaws pivotally connect the latter through the medium of toggle-links 19 with the forward ends of the handles. A seat 20 for the work is depressed between its ends, from which extend rings 21 about the ends of the jaw-pivoting bolt 14 to fasten the seat, which thus extends transversely across and bears against the 75 ends of the plate-tongues 12, permanently in centralized position between the jaws beneath the lips. Stops 22 are shown projecting adjustably at the inner sides of the handles to abut against each other and prevent 80 further inward movement of the handles than is necessary to bring the lips into meeting contact.

The tool is designed for use, more particularly, in joining together the overlapping ends of metal straps about baled cotton goods and other goods packed in bales. In that use, the strap-ends 23, in mutually overlapping relation, are introduced against the seat 20 to present their edges between the 85 jaws and register them with the grooves shown to be formed between the beveled under surfaces of the lips and the crimping-pins. By then pressing together the handles, the lips wedge the straps to hold them 90 against the raised seat-ends, causing the opposite strap-edges to enter the aforesaid grooves and be engaged by the beveled edges of the lips, which, in the initial pressure exerted on the handles, operate to curl the 95 strap-edges outwardly (with relation to the head of the tool) by engagement of the crimping-pins under those edges and their movement in the arc of a circle. In pressing the handles toward each other to bring 100 the jaws together, the intermeshing gears 10 serve to insure the accurately uniform movement of the jaws against the edges of the work, thereby to insure maintaining the important central relation of the seat, and thus 105 110

of the work, to the opposing jaws. Continued pressure upon the handles bends and cups the straps between their edge-portions into the depressed central portion of the seat, so that in the final part of the jaw-action, which closes the lips 16 together, the pins 17 force the outwardly-curved edge-portions of the straps toward each other, as represented in Fig. 6, and the parts coöperate 10 to bulge the crimped strap-sections into the shape illustrated at 24 in Figs. 7 and 8, thereby firmly locking the straps one within the other.

The compound leverage afforded by the 15 toggle-connections 19 between the handles and jaws renders the action of the tool very powerful by exerting comparatively little pressure on the handles.

What we claim as new and desire to secure 20 by Letters Patent is—

1. A tool for joining metal strap-ends having opposite side plates provided with forwardly extending tongue-sections, jaws pivoted together between the side plates and 25 provided with lips, crimping-pins projecting from the inner jaw-faces, a stationary seat for the work provided with marginal flanges embracing the tongue-sections of said

side plates and extending transversely across and connecting said plates between the jaws 30 and beneath the lips, handles pivoted between said plates, intermeshing gears on the forward ends of the handles and toggle-links connecting the jaws with the handles.

2. A tool for joining metal strap-ends 35 having opposite side plates provided with forwardly extending tongue-sections, jaws pivoted together between the side plates and provided with lips, crimping-pins projecting from the inner jaw-faces, a stationary seat 40 for the work provided with marginal flanges embracing the tongue-sections of said side plates and extending transversely across and connecting said plates between the jaws and beneath the lips, the marginal flanges of the 45 seat forming rings adapted to take over the ends of the jaw-arm pivoting bolt, handles pivoted between said plates intermeshing gears on the forward ends of the handles, and toggle-links connecting the jaws with 50 the handles.

ELLSWORTH E. FLORA.
JOHN F. MURPHY.
